UNITED STATES PATENT OFFICE.

PAUL P. LANTZ, OF TAMPA, KANSAS.

STACKING-MACHINE.

1,254,414.

specification of Letters Patent. Patented Jan. 22, 1918.

Application filed December 7, 1916. Serial No. 135,526.

To all whom it may concern:

Be it known that I, PAUL P. LANTZ, a citizen of the Republic of Switzerland, residing at Tampa, in the county of Marion, State of Kansas, have invented certain new and useful Improvements in Stacking-Machines, of which the following is a full and exact specification.

The present invention relates to machines for stacking grain and the like, and aims to provide an improved portable apparatus for stacking material of this character in an expeditious and effective manner. The improvements are designed for operation more particularly in the stacking of headed grain, though the use of the same is not confined to such material alone.

One of the objects of the invention is to devise a construction in which the stacker frame is provided with means for readily adjusting the frame at desired intervals for properly positioning the head or delivery end of the frame with reference to the stack being formed. For this purpose provision is made for effecting movement of the stacking frame and the conveyer carried thereby about various vertical and horizontal axes for obtaining the required adjustments in position of the head of the frame.

It is also an object to provide a convenient and readily operated mechanism for effecting the required adjusting movements, without interrupting the movements of the conveyer.

A further object is to equip the apparatus for portable use by providing a suitable wheel-supporting means adapted to permit all the necessary adjustments of the stacking frame while reliably and effectively supporting the same in all positions.

It is a further object to devise a strong, durable and compact construction and arrangement for embodying the proposed improvements. Other minor objects incident to the foregoing will appear in the course of the following detailed description.

With these various objects in view the invention will now be described with reference to the accompanying drawings illustrating one form of embodiment of the improvements, after which those features and combinations deemed to be novel will be severally set forth and defined in the appended claims.

In the drawings—

Figure 1 is a side elevation of a stacking

apparatus constructed in accordance with the present invention;

Fig. 2 is a view of the same in front elevation;

Fig. 3 is a sectional plan view (partly broken away) of the turn-table portion of the apparatus;

Fig. 4 is a sectional view of the stacker frame, the section being taken along the line IV-IV of Fig. 1;

Fig. 5 is an enlarged detail section of one of the take-up members for the stacking conveyer.

Referring to the said drawings in detail, these illustrate the apparatus as mounted upon a wheel support comprising a truck 2 having the bed portion 4 adapted to support a turn-table 6, between which and the bed 4 is interposed one or more sets of anti-friction rollers 8 so that the table is adapted for free pivotal movement about the central vertical axis at 10.

Upon this turn-table 6 is mounted the stacker frame proper 12, occupying an inclined position with its lower or receiving portion 12' in a relatively less inclined position for the convenient deposit of the grain or material to be stacked. The stacker frame is of closed-trough form (see Fig. 4) adapted for operation more particularly with headed grain, so that any loss of the grain will be prevented, and through the trough of said frame operates an elevating conveyer of the ordinary chain and sprocket wheel type, comprising the parallel endless chains 14 operating around sprocket wheels 16 at the head or delivery end of the frame, and similar wheels 18 at the foot or receiving end, the chains being connected at intervals by the toothed slats or conveyer flights 20.

The conveying run of the conveyer is upward through the trough of the frame 12, while the idle or return run is downward beneath the frame, guide rollers 22 being positioned at the turn from the main to the receiving portion 12' of the frame, as shown in Fig. 1. The upper sprocket wheels 16 are journaled on a shaft 23 provided with suitable take-up means comprising the slide blocks 24 having the rods 26 and springs 28 arranged to support the shaft yieldingly and automatically take up any undue slack in the conveyer chains. The lower sprocket wheels 18 are fixed to a foot shaft 30, to one end of which is also fixed a drive sprocket wheel 32 provided with a drive chain 34 op-

erating around a sprocket wheel 36 mounted on the shaft 38 carried by the frame 12 intermediate the ends thereof (see Fig. 4). To this shaft is also secured a pair of 5 sprocket wheels 39 in position to engage and assist in driving the conveyer chains 14, and adjacent the wheel 36 is also secured a sprocket wheel 40 connected by a sprocket chain 42 with a sprocket wheel 44 journaled 10 loosely on a shaft 46 mounted in brackets 44 carried by the turn-table 6. The sprocket wheel 44 is formed with a hub pulley 50 driven by a belt 52 from a pulley 54 having suitable clutch connection with the engine 15 56 also mounted on the table 6.

Means is provided for adjusting the angle and elevation of the stacker frame as follows. To the shaft 46 is fixed a worm gear 58 in mesh with a worm 60 mounted in the 20 bracket 62 on the table 6 and adapted to be turned by the hand-wheel 64. To the shaft 46 is also secured a lever arm 66, the opposite end of which is pivotally connected to the shaft 38. For coöperating with the arm 25 66 in the support of the stacker frame, a supporting frame 68 is provided, this latter frame being pivotally mounted in brackets 70 at opposite sides of the central vertical axis 10, and having the fork projections 72 30 carrying rollers 74 for engagement with the guide rails 76 secured at opposite sides of the frame 12. The greater portion of the weight of the stacker frame is at the rear of the shaft 38, so that the frame 12 tends to 35 throw the supporting frame 68 to the rear, and for holding said frame 68 in position for supporting the stacker frame at the proper angle to the axis 38 a windlass 78 is provided on the table 6, having the cable 80 40 extending around the guide roller 82 on said table and connected to a bail 84 attached to the opposite sides of said frame 68. A pawl 86 and ratchet wheel 88 on the windlass serve to retain the parts in the required position.

From the foregoing it will be apparent that a comparatively simple and efficient apparatus has been devised for carrying out the objects of the invention. The grain or 50 material to be stacked is fed to the receiving portion 12' of the stacker, whence it is carried by the conveyer out over the delivery end of the stacker on to the stack. By the arrangement of adjusting means provided, it 55 is clear that the position of the stacker may be readily altered in order to vary the location of its delivery end with reference to

the stacking point, as required. In accomplishing this adjustment of the apparatus, it will be observed that the entire apparatus may be swung about the axis of the pin 10; or the stacker frame may be moved about the axis of the shaft 38 by operation of the windlass 78; the lower end of said frame may be raised or lowered by the operation of the wheel 68; and the frame may be bodily swung about the axis of the shaft 46 and also intermediate adjustments obtained by the combined manipulation of the wheel 68 and windlass 78, as will be readily understood. A clutch lever 90 of suitable length (see Fig. 1) may be provided for convenient control of the engine from the stack, if desired.

While the foregoing represents what is 75 now deemed to constitute the preferred form of embodiment of the improvements, the right is reserved to such formal changes and modifications as may fairly fall within the scope of the appended claims. 80

Claims:

1. A stacking apparatus comprising a supporting structure, a horizontal shaft carried by said structure, an arm fixed to said shaft, a stacker frame pivoted to said arm, a stacker conveyer operating around said frame, means geared to said shaft for turning the same for angularly adjusting said frame about the axis of said shaft, and drive elements loosely journaled on said shaft and 85 provided with drive connections to said conveyer for operating the latter.

2. A stacking apparatus comprising a supporting structure, a stacker frame, a supporting arm carried by said structure and pivotally connected to said stacker frame, means for angularly adjusting said arm with reference to said supporting structure in order to raise and lower said frame, 95 guide rails secured to said stacker frame 100 said arm and one of the ends of said frame, a swinging frame pivotally mounted on said supporting structure and provided with rollers embracing opposite sides of each of said guide rails for coöperating with said arm in supporting said stacker frame, a bail pivoted to the opposite sides of said swinging frame, a cable connected to said bail, and means mounted on said supporting structure for operating said 110 cable to adjust the position of said supporting frame.

PAUL P. LANTZ.
